US00D921610S

(12) **United States Design Patent** (10) **Patent No.:** **US D921,610 S**
(45) **Date of Patent:** **** Jun. 8, 2021**

(54) **AUDIO ASSEMBLY**

(71) Applicant: **Google LLC**, Mountain View, CA (US)

(72) Inventors: **Gina Reimann**, Los Gatos, CA (US); **Kenneth Sweet**, San Francisco, CA (US); **Luke David Mastrangelo**, San Francisco, CA (US); **Peter Michael Cazalet**, Los Gatos, CA (US); **Maj Isabelle Olsson**, Sunnyvale, CA (US)

(73) Assignee: **GOOGLE LLC**, Mountain View, CA (US)

(**) Term: **15 Years**

(21) Appl. No.: **29/748,623**

(22) Filed: **Aug. 31, 2020**

Related U.S. Application Data

(63) Continuation of application No. 29/664,264, filed on Sep. 24, 2018, now Pat. No. Des. 896,781, which is a continuation-in-part of application No. 29/612,920, filed on Aug. 4, 2017, now Pat. No. Des. 844,586.

CLAIM

The ornamental design for an audio assembly, as shown and described.

DESCRIPTION

FIG. 1 is a front perspective view of an audio assembly according to our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof; and,

FIG. 7 is a bottom elevation view thereof.

Broken lines are environmental only and form no part of the claimed design.

1 Claim, 5 Drawing Sheets
